UNITED STATES PATENT OFFICE.

WILLIAM SCHWIER, OF TACOMA, WASHINGTON, ASSIGNOR OF ONE-HALF TO FRANK HAUBROCK, OF TACOMA, WASHINGTON.

MONORAIL FROG.

Application filed August 23, 1921. Serial No. 494,674.

To all whom it may concern:

Be it known that WILLIAM SCHWIER, a citizen of the United States of America, residing at Tacoma, in the county of Pierce, 5 and State of Washington, has invented new and useful Improvements in Monorail Frogs, of which the following is a specification.

The object of the invention is to provide 10 a simple and efficient construction of monorail frog for use in connection with and operation of a simultaneous operation to a switch rail, under conditions providing for a continuous rail tread surface in passing 15 into and out of a siding to avoid the gap or interval ordinarily required to provide a passage for the wheel flange; and with this object in view the invention consists in a construction and combination of parts of 20 which a preferred embodiment is shown in the accompanying drawings wherein:—

Figure 1 is a plan view of a switch mechanism including a monorail frog embodying the invention.

Figure 2 is a sectional view in detail taken 25 on the plane indicated by the line 2—2 of Figure 1.

Figure 3 is a similar sectional view taken 30 on the plane indicated by the line 3—3 of Figure 1.

Figures 4 and 5 are respectively detail 35 plan views of the cradles.

Figures 6 and 7 are respectively plan views 40 in detail of the carrier and transmission disks.

The apparatus is shown in connection with the main track rails 10 and siding track rail 11 with the switch tongue 12 connected by a switch bar 13 with the switch stand 14 having an operating shaft 15 carrying a crank arm 16.

The frog rail 17 is arranged at the intersection of the siding and main track rails with the center of its length at the point 45 of intersection of the lines of said rails and is adapted for pivotal movement about an axis located substantially at the point of intersection of the lines of said rails to occupy a position selectively in alignment 50 with either the siding or the main track rail, and terminally said frog rail is supported by carrier disks 18, revolvably mounted in seats 19 constituting depressed portions of a cradle 20 consisting of a frame of metal 55 secured to and resting upon the cross ties 21

and securely fastened thereto by spikes or the equivalents thereof, the seats being depressed to occupy the spaces between the ties as clearly indicated in Figures 2 and 3.

The mounting of the carrier disks in the 60 seats is effected by means of central pivot bolts 22 and the connection of the end portions of the frog rail with the carrier disks is effected by means of clips 23 which engage 65 the foot of the frog rail and are provided with pivot bolts 24 engaging openings 25 in peripheral ears 26 of said disks.

Motion is communicated to the carrier disks through connecting rods 27, preferably 70 provided with turn buckles 28 or like adjusting means, from transmission disks 29 which are revolvably mounted in seats 30 constituting depressed portions of a cradle 31 similar in construction to the cradle 20 and supported by the cross ties with the seats 75 30 occupying positions between the ties so that as with the carrier disks the transmission disks are disposed below the plane of the body portions of the cradles and below the planes of the upper sides of the ties so 80 that the connecting rods 27 extend beneath the rails in the intervals between the ties.

The transmission disks are connected together for simultaneous movement in the same direction by a connecting rod 32 and 85 are limited in rotary movement and are held against tilting movement by segmental slots 33 engaging headed guide pins 34 in the seats 30. Motion is communicated to the transmission disks from the crank 16 of the switch 90 operating shaft 15 by a rod 35 which in common with the connecting rod 32 is preferably provided with an offset or curved portion 36 affording increased leverage in communicating motion to the transmission disks. 95

In operation when the shaft 15 is turned to open or close the switch or shift the switch tongue from one position to the other the frog rail through the simultaneous movements of the transmission and carrier disks 100 is shifted into alignment either with the main rail or with the siding rail, according to the direction of movement of the switch tongue, to provide an unbroken tread surface for the car wheels.

The cradle 20 which is disposed beneath the frog rail is provided with a central clip 37 and terminal clips 38 and 39 for engagement by the frog rail in its adjusted positions, the clips 38 and 39 respectively being 110

disposed to engage and properly position the adjacent extremities of the main and siding track rails which are to be connected alternatively by the frog rail.

- 5 While there is a movement of each of the clips 23 in a path of which the center is not coincident with the axis of movement of the frog, the extent of angular movement of the latter is relatively so small that a comparatively slight looseness in the engagement of the clips with the frog or the attachment of the clips to the disks or in the mounting of the disks will be sufficient to compensate for any variation in the distance between the clips in the swinging movement of the frog from one position to the other and thereby avoid such a binding or jamming of the parts as would in any way interfere with the operative position of the frog.

Having described the invention, what is claimed as new and useful is:—

1. A monorail frog for actuation simultaneously with a switch tongue having a frog rail disposed at the intersection of the siding and main track rails for pivotal movement in a horizontal plane into aligning relation alternatively with said rails, and revolute carrier disks respectively supporting the extremities of said frog rail and operatively connected with the switch tongue.

2. A monorail frog for actuation simultaneously with a switch tongue having a frog rail disposed at the intersection of the siding and main track rails for pivotal movement in a horizontal plane into aligning relation alternatively with said rails, a tie supported cradle arranged beneath said frog rail and provided with seats, and carrier disks revolutely mounted in said seats in supporting relation with the extremities of said rail, the carrier disks being operatively connected with the switch tongue.

- 45 3. A monorail frog for actuation simultaneously with a switch tongue having a frog rail disposed at the intersection of the siding and main track rails for pivotal movement in a horizontal plane into aligning relation alternatively with said rails, revolute carrier disks arranged beneath and having pivotal supporting connection with the frog rail near its extremities, revolute transmission disks operatively connected respectively with the carrier disks and connected together for simultaneous movement, and means for communicating rotary movement in opposite directions to said transmission disks.

- 60 4. A monorail frog for actuation simultaneously with a switch tongue having a frog rail disposed at the intersection of the siding and main track rails for pivotal movement in a horizontal plane into aligning relation alternatively with said rails,

cradles arranged respectively beneath said frog rail and adjacent to the opposite main rail and provided with depressed seats, carrier and transmission disks revolutely mounted respectively in the seats of said cradles, the transmission disks being connected together for simultaneous movement and each transmission disk being connected with one of the carrier disks, and means for communicating motion simultaneously to said transmission disks and the switch tongue.

5. A monorail frog for actuation simultaneously with a switch tongue having a frog rail disposed at the intersection of the siding and main track rails for pivotal movement in a horizontal plane into aligning relation alternatively with said rails, cradles arranged respectively beneath said frog rail and adjacent to the opposite main rail and provided with depressed seats, carrier and transmission disks revolutely mounted respectively in the seats of said cradles, the transmission disks being connected together for simultaneous movement and each transmission disk being connected with one of the carrier disks, and means for communicating motion simultaneously to said transmission disks and the switch tongue, said carrier disks having foot receiving clips for engagement with the frog rail near its extremities and revolutely mounted upon the disks.

6. A monorail frog for actuation simultaneously with a switch tongue having a frog rail disposed at the intersection of the siding and main track rails for pivotal movement in a horizontal plane into aligning relation alternatively with said rails, cradles arranged respectively beneath said frog rail and adjacent to the opposite main rail and provided with depressed seats, carrier and transmission disks revolutely mounted respectively in the seats of said cradles, the transmission disks being connected together for simultaneous movement and each transmission disk being connected with one of the carrier disks, and means for communicating motion simultaneously to said transmission disks and the switch tongue, the connections between the transmission and carrier disks being adjustable to vary the relative positions thereof.

7. A monorail frog for actuation simultaneously with a switch tongue having a frog rail disposed at the intersection of the siding and main track rails for pivotal movement in a horizontal plane into aligning relation alternatively with said rails, cradles arranged respectively beneath said frog rail and adjacent to the opposite main rail and provided with depressed seats, carrier and transmission disks revolutely mounted respectively in the seats of said cradles, the transmission disks being con-

nected together for simultaneous movement and each transmission disk being connected with one of the carrier disks, and means for communicating motion simultaneously to 5 said transmission disks and the switch tongue, the transmission disks being provided with slot and pin means for limiting the rotary movement thereof.

8. A monorail frog for actuation simultaneously with a switch tongue having a frog rail disposed at the intersection of the siding and main track rails for pivotal movement in a horizontal plane into aligning relation alternatively with said rails, 10 cradles arranged respectively beneath said frog rail and adjacent to the opposite main

rail and provided with depressed seats, carrier and transmission disks revolubly mounted respectively in the seats of said cradles, the transmission disks being connected together for simultaneous movement and each transmission disk being connected with one of the carrier disks, and means for communicating motion simultaneously to 20 said transmission disks and the switch tongue, said first-named cradle being provided with clips for engaging the feet of the adjacent portions of the main and siding rails.

In testimony whereof he affixes his sig- 25 nature.

WILLIAM SCHWIER.
